UNITED STATES PATENT OFFICE.

JOHN F. DUSTIN, OF LAWRENCE, MASSACHUSETTS.

WARP STOP-MOTION.

1,109,212.

Specification of Letters Patent.

Patented Sept. 1, 1914.

Application filed February 24, 1913. Serial No. 750,112.

To all whom it may concern:

Be it known that I, JOHN F. DUSTIN, a citizen of the United States, residing at Lawrence, county of Essex, State of Massachusetts, have invented an Improvement in Warp Stop-Motions, of which the following description, in connection with the accompanying drawing, is a specification, like characters on the drawing representing like parts.

This invention relates to warp stop motions of that type wherein the detectors are made of resilient flexible material and the feeler mechanism is so constructed that whenever a warp breaks and the corresponding detector falls, the action of the feeler on the fallen detector will not only cause stoppage of the loom, but will also flex the detector in such a way as to open the sheet of warp threads adjacent said detector, thus giving the weaver a clear indication as to the position of the broken thread.

The object of my present invention is to provide a novel feeler mechanism which effects this separation of the warp threads when a detector falls, but which is very simple in construction, inexpensive to manufacture and easy to apply to a loom.

Referring to the drawings wherein I have illustrated a preferred embodiment of my invention, Figure 1 is a front elevation of a section of the warp stop motion showing the manner in which it operates; Fig. 2 is a sectional view on substantially the line $x-x$, Fig. 1; Figs. 3 and 4 are fragmentary details of the stop motion; Fig. 5 is an enlarged view of a part of the feeler mechanism showing one position thereof; Fig. 6 is a similar view showing the position of the parts when a detector has fallen; Fig. 7 is a section on the line $y-y$, Fig. 5; Figs. 8, 9 and 10 are views similar to Figs. 5, 6 and 7, respectively, but showing a different embodiment of the invention.

In the drawings 1 indicates a part of a loom frame, 2 the whip roll over which the warp threads 3 pass, and 4 the base rod. These parts are such as are usually found in looms and form no part of my present invention, and as the latter is concerned merely with the warp stop motion I have not deemed it necessary to further illustrate the loom.

My warp stop motion includes the usual

detectors 5, one for each of the warp threads, and the detectors may either be in the nature of drop wires separate and distinct from the heddle and placed adjacent the whip roll, or they may be the heddles themselves, as desired.

In the present embodiment of my invention I have shown the detectors as in the form of drop wires separate from the heddles and harness frames. Each of these detectors is provided with a thread-receiving opening through which the warp thread extends and is also provided with a feeler-receiving slot through which the feeler members pass. The drop wires may be suspended on the warp threads either from above or from below the feeler mechanism. In the embodiment shown in Figs. 1 to 6 the feeler mechanism is above the warp threads, in which case the thread-receiving slot 6 is at the lower end of the detector and the feeler-receiving slot 7 is at the upper end of the detector.

The feeler mechanism comprises two feeler members 8 and 9 which extend across the loom and through the apertures 7 in the detectors. These feeler members are arranged to have a longitudinal movement relative to each other as usual in warp stop motions, but they are so constructed that when a detector falls such longitudinal movement will cause the flexing or bending of the drop wire, as above described. While it would be within my invention to make either or both of the feeler members 8 and 9 movable so long as the relative movement is secured, I prefer to make the member 8 a movable member and the member 9 a rigid or stationary member which is in the nature of a support for the movable member. The member 9 is herein shown as comprising two plates between which the member 8 is received and reciprocates. The mechanism for giving reciprocation to the member 8 will be presently described.

The member 9 is provided with a plurality of feeler-flexing projections 10 of peculiar shape, and the member 8 is provided with cooperating feeler-flexing projections 11 of special shape. Each projection 11 is provided on each side at its base with a detector-arresting shoulder 12 and with an inclined surface 13 above said shoulder. The upper end of each projection 11 is preferably pointed or rounded so that when a

detector drops it will not be retained on the top of the projection but will slide down one of the sides thereof into the space between the adjacent projections. The projections 10 on the member 9 are each provided with a detector-flexing nose 14 which is situated above the line of the shoulders 12 on the member 8 and with an inclined face 15 beneath the nose. The upper side of each of the projections 10 is also either pointed or rounded so as to make it impossible that a detector shall remain on top of the projection when it falls. The detectors 5 are so constructed that the depth of the solid portion 16 above the upper end of the feeler receiving slot 7 is somewhat greater than the distance between the nose 14 and the top edge 17 of the feeler members, so that when any detector falls, as shown by the detector 5^a in Fig. 5, a portion of this solid portion 16 will come opposite the nose 14 on the adjacent projection 10.

In the operation of the device the feeler member 8 is reciprocating continuously while the loom is running, said reciprocations carrying it from its central position shown in Fig. 5 to the position shown in Fig. 6 on either side of said central position, said reciprocations being of a length equal to the distance between adjacent projections. It will be noted in this connection that the projections on each of the members are spaced the same distance apart. When any detector drops because of the breakage, unless due slackness, exhaustion, or any other fault in the corresponding warp thread, said fallen detector will drop into the space between the adjacent projections because of the rounded or pointed shape of the top of the projections, as seen by the detector 5^a in Fig. 5. During the movement of the feeler member subsequent to the time when the detector has fallen, the detector-flexing nose 14 of one of the projections will engage the solid part of the detector and the top edge of the slot 7 in the detector will come into engagement with the detector-arresting shoulder 12. Since the shoulder 12 and the nose 14 act on the detector in different horizontal planes, it will follow that the continued relative movement of the feeler members will bend the portion 16 of the detector over into the position shown in Fig. 6 until said portion is confined between the inclined faces 15 and 13, which faces are parallel to each other. This bending of the upper portion of the detector will flex the whole detector, as shown in Fig. 6, and the lower end of the detector will be forced laterally against the adjacent detectors, thus pushing them to one side and opening up a space in the sheet of warp threads. When the detector is finally brought into the positions shown in Fig. 6, further movement of the feeler member 8 is prevented, and the

stopping mechanism then comes into play to stop the loom. This manner of flexing a fallen detector has the advantage that said detector opens up a considerable gap in the sheet of warp threads which gives a clear indication to the operator where the broken warp thread is located. 73

In Figs. 8, 9 and 10 I have shown a construction which is similar to that above described except that the feeler members are located below the warp threads. In this case the feeler-receiving slot 7^a is located in the bottom of the detector, while the warp-thread-receiving opening 6^a is located in the upper side of the detector, each detector having a threading opening 19 to permit the warp thread to be entered into its slot. In this case the detector-flexing noses and shoulders of the feeler members act on the solid portion 16^a of the detector and the detector is flexed both above and below this portion, as seen in Fig. 9, thus providing for displacing the inoperative detectors on both sides of the fallen detector. 80 85

While any suitable means may be used for giving reciprocating movement to the feeler member 8 without departing from the invention, I have found that the mechanism shown in Figs. 1 and 2 is a satisfactory one. 90

21 designates a rock shaft journaled in suitable bearings 29 on the loom frame. This rock shaft has fast thereon an arm 20 which is pivotally connected to the feeler member 8. Said shaft also has thereon an arm 22 which is pivotally connected to a collar 23 that is yieldingly connected to an actuating rod 24, said rod 24 being connected to any suitable moving part of the loom by which it may be given a proper up-and-down reciprocating movement. The connection between the collar 23 and the actuating rod 24 is provided for by two springs 25 situated either side of the collar 23 and encircling the rod 24 and engaging collars 26 fast on the rod 24. The up-and-down movement of the rod 24 is, therefore, communicated to the feeler member 8 through the springs 26 and rock shaft 21. The rock shaft 21 is also provided with an arm 27 having a pin or projection 30 extending laterally therefrom. This projection has engagement with a cam surface 28 carried by the end of a lever 31 that is pivoted on the loom frame at 32. The lever 31 is connected by a link 33 with one end of a guard member 34 that is pivoted at its other end to the front of the loom frame, as shown at 35. The rocking movement of the rock shaft 21 operates through the projection 30 and cam surface 28 to cause a rocking movement of the lever 31 and a consequent rising and falling movement of the guard member 34. The lay 35 of the loom is provided with a dagger or finger 36 which normally rests on the guard member 34. 110 120 125 130

37 is a knock-off lever pivoted to the loom frame at 38 and adapted to engage the usual shipper-lever 39. The lower end of the knock-off lever 37 engages a knock-off slide 40 which is mounted for sliding movement on the loom frame 1 and which is provided with a finger 41 adapted to be engaged by the dagger or finger 36 on the lay.

The projection 30 moves in the arc of a circle having the axis of the shaft 21 as its center and, therefore, as the arm 27 rocks to either side of the central position shown in Fig. 3, as shown by dotted lines, the lever 31 will be turned thereby to elevate the guard finger 34. When, however, the parts are in the central position shown in full lines Fig. 3, the guard 34 is lowered so that the dagger 36 is in a position to engage the finger 41 of the knock-off slide. The parts are so timed that the guard finger 34 is raised each time that the lay beats up so long as the feeler member 8 is permitted to have its full movement, and, therefore, the finger 36 is held in its inoperative position. Whenever a detector falls, however, through a fault in a warp thread and the movement of the feeler member 8 is thereby arrested, then the cam member 28 is held in its central position, and when the lay beats up the dagger 36 which is now in its lowered position will engage the projection 41 and thus operate the knock-off lever to stop the loom. When the feeler member 8 is thus arrested the springs 25 allow the movement of the actuator rod 24 without breakage of the parts.

Having fully described my invention, what I claim as new and desire to secure by Letters Patent is:—

40. 1. In a warp stop motion, the combination with a plurality of resilient flexible slotted detectors normally sustained by the warp threads, of two feeler members extending through the slots of said detectors, and means for giving said members a relative movement in the direction of their length, one of said members having projections thereon, each presenting a detector-arresting shoulder at its base and an inclined surface above said shoulder, and the other member having projections, each presenting a lateral detector-flexing nose situated above said shoulder.

55. 2. In a warp stop motion, the combination with a plurality of resilient flexible slotted detectors normally sustained by the warp threads, of two feeler members extending through the slots of said detectors, and means for giving said members a relative movement in the direction of their length, one of said members having projections thereon, each presenting a detector-arresting shoulder at its base and an inclined surface above said shoulder, and the other member having projections, each presenting a

lateral detector-flexing nose situated above said shoulder, said nose having its under face inclined.

3. In a warp stop motion, the combination with a plurality of resilient flexible slotted detectors normally sustained by the warp threads, of two feeler members extending through the slots of said detectors, and means for giving said members a relative movement in the direction of their length, one of said members having projections thereon, each presenting a detector-arresting shoulder at its base and an inclined surface above said shoulder, and the other member having projections, each presenting a lateral detector-flexing nose situated above said shoulder, said nose having an under face inclined substantially parallel to said inclined surface.

4. In a warp stop motion, the combination with a plurality of resilient flexible slotted detectors normally sustained by the warp threads, of two feeler members extending through the slots of said detectors, and means for giving said members a relative movement in the direction of their length, one of said members having projections thereon, each presenting on both sides thereof a detector-arresting shoulder at its base and an inclined surface above said shoulder, and the other member having projections each presenting on both sides thereof a lateral detector-flexing nose situated above the shoulder.

5. In a warp stop motion, the combination with a plurality of resilient flexible slotted detectors normally sustained by the warp threads, of two feeler members extending through the slots of said detectors, and means for giving said members a relative movement in the direction of their length, one of said members having projections thereon, each presenting on both sides thereof a detector-arresting shoulder at its base and an inclined surface above said shoulder, and the other member having projections each presenting on both sides thereof a lateral detector-flexing nose situated above the shoulder, the under face of each nose having an inclined surface parallel to the first-named inclined surface.

6. In a warp stop motion, the combination with two feeler members, of means to give said members a relative movement in the direction of their length, a plurality of resilient flexible detectors embracing said feeler members and normally sustained by the warp threads, said members having projections, the projections of one member presenting inclined surfaces and those of the other member presenting detector-flexing noses situated above said surfaces whereby a fallen detector will be forced against an inclined surface by one of the noses and thereby flexed out of its normal position.

7. In a warp stop motion, the combination with a plurality of resilient flexible slotted detectors normally sustained by the warp threads, of two feeler members extending 5 through the slots of said detectors, one member having detector-arresting shoulders and inclined surfaces above the shoulders and the other member having detector-flexing noses situated above the shoulders whereby 10 when any detector drops owing to a fault

said detector is engaged between the nose and the inclined surface and thereby flexed out of its normal position.

In testimony whereof, I have signed my name to this specification, in the presence of 15 two subscribing witnesses.

JOHN F. DUSTIN.
